RAIL JOINT

George Langford, Joliet, Ill., assignor to McKenna Process Company of Illinois, Joliet, Ill., a corporation of Illinois

Original application May 1, 1935, Serial No. 19,158. Divided and this application December 2, 1935, Serial No. 52,526

4 Claims. (Cl. 238—243)

The present invention relates to bars or fish-plates used to join rails together in track, and in particular to a novel form of bar for use on worn rails.

5 Crowning, oversizing, incurving and other shapings of bars to repair worn rail joints are so well known that any description of the present state of the art appears unnecessary. My invention is a bar shaped for use on worn rails. Its 10 novelty lies in its form and in the new and useful purpose it accomplishes. Its main purpose is to secure a proper fitting to rails so variously worn as to prevent proper fitting with any one known form of bar of its type. My invention will 15 be clearly understood from the following description and accompanying drawing. It is a divisional application arising out of my copending application, Serial No. 19,158, filed May 1, 1935.

All of the figures of the drawing represent 20 cross-sectional views of one side of the top of worn rail joints. These views are taken at the central six inches or so of the joint where most wear occurs. All of the figures are similarly lettered.

25 In the drawing:—

Fig. 1 represents a moderately worn joint comprising a bar of ordinary head contact type;

Fig. 2 represents the worn rail of Fig. 1 to which is fitted an unworn bar of head free type;

Fig. 3 is similar to Fig. 1 except that the joint 30 is badly instead of moderately worn;

Fig. 4 illustrates the type of rail wear present in Figs. 1 and 2;

Fig. 5 illustrates the type of rail wear present 35 in Fig. 3;

Fig. 6 represents the bar of my invention fitted to a rail worn as in Fig. 4;

Fig. 7 represents the bar of my invention fitted to a rail worn as in Fig. 5.

40 In the shaping of bars to fit worn rail ends, the most common custom is to crown or make oversized the top central fishing surface of a bar of ordinary head contact type. This results in a bar of oversized or above normal fishing height at the central portion at least of the joint. The greatest wear in a joint is for six inches or more 45 at the top central portion, and so the top fishing surface of the bar is crowned there to compensate for the worn, increased fishing height of the rail ends.

50 In addition to the above practice, there is considerable use of bars of head free type on worn rails. A head free bar has clearance at its top, from the under surface of the rail head. Its fishing surface engagement occurs on its top

inner fillet which contacts the rail fillet connecting the rail head and web. An ordinary head contact bar has fishing contact with the under surface only of the rail head and not with the rail head fillet joining the rail head and web. It 5 is claimed that a normal head free bar of uniform height throughout its length is suitable for worn rails, for the reason that it is not intended to contact the under surface of the rail head, worn or unworn, its contact being with the rail 10 head fillet. If an ordinary head contact bar had been previously used, presumably its lack of contact with the rail head fillet would have left that fillet unworn, and the top inner fillet of the head free bar would fit into it regardless of the wear 15 on its under surface. This is true in some cases but not in others as I have determined by observation.

Fig. 1 is a fragmentary top end view of the 20 central portion of a worn rail joint. 1 represents the rail head, and 2 the head or top member of the bar, the latter being of head contact type. In the worn joint, the bar is shown by full lines. Its position in the original unworn joint is shown by dotted lines. The same is true of all the 25 figures, and the same lettering is used throughout, for convenience of explanation.

In Fig. 1, the original contact surface $a-b$ of the rail has shifted by wear to $a'-b'$, leaving in 30 many cases a rail-lip $a-a'$. Fig. 1 may be designated as a good example of a moderately worn joint. The bar head has been drawn in, but not enough to engage at $b'-c'$ with the rail fillet although the latter $d-c^2$ is somewhat shortened 35 at its top by the jog $b'-d$ where the bar fillet $b'-c'$ has partially intruded.

Fig. 2 represents an ordinary head free bar 40 fitted to the worn rail head of Fig. 1. This bar has rail fillet contact at $d-c^2$, less than it would have had on the unworn rail, and it cannot soon gather up any increase by wear farther out at b' 45 as intended, for the reason that the rail surface originally $a-b$ is worn beyond its reach to $a'-b'$. Increased wear of the rails over that shown in Fig. 1, would make this condition worse.

In Fig. 3, the wear of the head contact bar in 50 Fig. 1 has progressed until the bar fillet $b-c$ has contacted and worn away the rail fillet so that the latter is now $b'-c^2$. Obviously the normal head free bar of Fig. 2 contacting only at c^2 , can not be fitted suitably to the worn rail head of Fig. 3 without some alteration. To fit surface $b'-c^2$, it must be made crowned or oversized 55 at its central portion to fill up the space $b'-d-c^2$. However if this be done to suit the

worn rail condition of Fig. 3 it will encounter an obstacle in the irregular surface $b'-d-c^2$ present in the worn rail condition of Fig. 1.

Fig. 4 represents the moderately worn rail condition of Fig. 1, and Fig. 5 represents the badly worn rail condition of Fig. 3. Evidently the same head free bar cannot fit both, and any compromise would not be satisfactory, and more than would a crowned or uncrowned head contact bar. Inasmuch as the head free bar depends primarily upon rail fillet contact, its top inner fillet b^2-c^2 of Fig. 2 should be uncrowned when used on the rail of Fig. 5. The present state of the art of fitting bars to worn rails exacts greater precision than can be arrived at by any compromise in a bar of this kind to suit the two worn conditions, commonly occurring as are represented by Figs. 4 and 5.

In the manufacture of ordinary crowned head contact bars, I have found another obstacle to precise fitting. This obstacle is the rail lip $a-a'$ resulting from wear. It is not always present but occurs frequently and I find it a considerable source of trouble. When a head contact bar is crowned, its top outer corner is at "a". If the rail lip $a-a'$ is present, as it frequently is, the result is an unsatisfactory fit.

My invention is a bar adapted to the two worn rail conditions of Figs. 4 and 5 and to the obstacle presented by the rail lip $a-a'$, none of which are met by any design of bar that I know of. The bar of my invention is also designed to secure as much area of fishing contact at the central portion of the joint as can be secured. The space is limited beneath the rail head, and the width of contact $a-b$ in a head contact bar, is considered by many engineers as not enough. This width of contact is less and at least no greater in a head free bar than in one of head contact type.

My invention has as its basis a bar of full head contact type, on which U. S. Patent No. 1,759,458 was issued to me May 20, 1930. This bar has rail head contact $a-b$ plus rail fillet contact $b-c$. Its top outer corner instead of being at "a" is spaced substantially inward, thereby avoiding the rail lip $a-a'$ and overcoming one of the difficulties previously described. The present invention comprises crowning the rail head contacting surface $a-b$ but not the rail fillet contacting surface $b-c$. The top of this bar and its application to the worn rail conditions of Figs. 4 and 5, is shown in Figs. 6 and 7.

In Fig. 6, the bar is fitted to a worn rail similar to that of Figs. 1 and 4. The top fishing surface is raised to $a'-b'$ at its central portion, and contacts the worn surface $a'-b'$ of the rails at the joint's central portion.

Fillet $d-c^2$ of the bar is normal and uncrowned so as to fit the rail head fillet $d-c^2$. The rail fishing contact is then $a'-b'$ plus $d-c^2$. This is much more central contact than is possible in the case of the head contact or of the head free bar.

Fig. 7 represents the bar of Fig. 6 fitted to a badly worn rail similar to the rail of Figs. 3 and 5. There is rail head contact $a'-b'$, but although there is contact at c^2 , there may be little or no rail fillet contact on $d-c^2$ above c^2 . $b'-d-c^2$ on first application represents more or less empty space, for the reason that the bar's fillet $d-c^2$ is not crowned or enlarged to fill it. If fillet $d-c^2$ of the bar were crowned or enlarged, it would encounter the obstacle $b'-d-c^2$ present in the worn rail of Fig. 6. In Fig. 7 as

wear occurs at $a'-b'$ and this surface of the joint shifts upward, gap $b'-d-c^2$ will close, and there will eventually be full head contact in Fig. 7 as in Fig. 6. The bar of my invention has the important object of avoiding the obstacle $b'-d-c^2$ present in cases of moderate rail wear. Contact $d-c^2$ is lost initially but it occurs by wear eventually. Furthermore although there may be some loss of this contact initially there is still an initial contact $a'-b'$ to depend upon, and this contact is at least no less than is available in the ordinary head contact or head free bar.

Briefly described, my invention is a full head contact bar crowned on its top surface and uncrowned on its top inner fillet. More specifically the novelty is restricted to the central portion of the bar, the end portions being of any shape that permits the central fitting as described.

The rails to which such a bar is fitted are limited to ones of ordinary type on which either ordinary head contact or full head contact bars may be used, the under side of the rail head being a surface in one plane from the top of the head-web fillet to the outer corner of the under side of the rail head, and the rail head being as wide at least at the bottom as at the top. The bar itself is restricted to a top contacting surface conforming to the under side of an ordinary type of rail as previously defined. The central crowning of this top surface, and the absence of central crowning on the top inner fillet is the substance of my invention, such a structure being adaptable to worn rails of ordinary type wherein the rail head-web fillet is either worn or unworn centrally.

My invention may also be applied to an ordinary head contact bar. In Fig. 1, which shows a head contact bar worn in a joint, it will be noticed that the top inner fillet of the bar encounters the obstruction $b'-d$ in a rail worn as in Fig. 1. If the top inner fillet were not raised above its normal rail fishing height, it would not be obstructed at $b'-d$. This would permit of the bar's longer useful life as a head contact bar and would further continue its life as a full head contact bar in such cases where the bottom member so provided.

The end portions of the bar are made of less effective rail fishing height than the center portion either by reducing their height to normal or below normal by deflecting them outwardly or in any manner that permits of a correct central fit of the bar to the worn rail ends. Although not preferable, my invention may be applied to the bottom fishing surface as well as to the top one. As the principle of application is the same at the bottom as at the top, it is not thought necessary to illustrate the application of my invention to a bottom fishing surface.

What I claim is:

1. In a worn rail joint including worn rail ends of ordinary type, a bar comprising a central portion with its top surface in fishing contact with the under side of the heads of the worn rail ends and with its top inner fillet in contact with the bottom at least of the corresponding rail head fillet, said top surface of said central portion of the bar being raised to above normal fishing height, and said inner fillet being of normal and uniform height throughout the center portion and end portions of the bar.

2. In a worn rail joint including worn rail ends of ordinary type, a bar comprising a central portion with its top surface in fishing contact with the under side of the heads of the worn rail ends

and with its top inner fillet in contact with the corresponding rail head fillet, said top surface of said central portion of the bar being raised to above normal fishing height, and said top inner fillet being of normal and uniform height throughout the center portion and end portions of the bar.

3. A rail joint bar providing for top and bottom fishing contact at its center portion and end portions with worn rail ends of ordinary type and having one at least of its top and bottom fishing surfaces raised to above normal rail fishing height at its center portion at least, the inner fillet of the bar at said center portion being of not above its normal rail fishing height.

4. A rail joint bar for use on worn rails of

ordinary type, wherein the head-web fillet of the rails may or may not have become worn at the center portion of the joint, said bar providing for top and bottom rail fishing contact at its center portion and end portions, the top surface of the bar being raised to above normal fishing height at its center portion to provide contact with the worn under side of the head at the center portion of the joint, and the top inner fillet of the bar being of normal height at its center portion and end portions, and in contact with the head-web fillet of the rails and unworn portions of said head-web fillet when the bar is applied to the rail ends in a joint.

GEORGE LANGFORD. 15
